(57) **CLAIM**

The ornamental design for a cap for a medicine container, as shown and described.

DESCRIPTION

FIG. 1 is a perspective view of a cap for a medicine container showing our new design;
 FIG. 2 is a front elevational view thereof;
 FIG. 3 is a rear elevational view thereof;
 FIG. 4 is a left side elevational view thereof;
 FIG. 5 is a right side elevational view thereof;
 FIG. 6 is a top plan view thereof;
 FIG. 7 is a bottom plan view thereof; and,

FIG. 8 is a reference view thereof showing the cap for a medicine container in a position of use on an unclaimed container drawn in broken lines.

The broken lines illustrating a container depict environment and form no part of the claimed design. All other broken lines depict portions of the cap for a medicine container that form no part of the claimed design.
